UNITED STATES PATENT OFFICE.

HARRY DEL MAR, OF NEW YORK, N. Y., ASSIGNOR TO BOILERS AND ENGINEERING COMPANY, OF JERSEY CITY, NEW JERSEY, A CORPORATION OF NEW JERSEY.

WATER-TUBE BOILER.

No. 842,084.

Specification of Letters Patent.

Patented Jan. 22, 1907.

Application filed June 26, 1906. Serial No. 323,428.

To all whom it may concern:

Be it known that I, HARRY DEL MAR, of the city, county, and State of New York, have invented a new and Improved Sectional Water-Tube Steam-Boiler, of which the following is a full, clear, and exact description.

My invention relates to steam-boilers of the water-tube type; and the object of my invention is to produce a sectional water-tube steam-boiler of the cross-tube style having side water legs or drums from which issue a set of tubes designed to go under the cross-sectional series of tubes and to fill in or occupy the space made by the incline of the cross-tube series.

Another object of my invention is to produce a boiler having a door-header or manifold or series of manifolds used in the construction of what is termed a "low-set side-fired cross-tube sectional boiler," so that each manifold is connected by a tube to the one next to it, and each manifold is also connected to a mud-drum or water-leg for depositing scale or sediment and feeding water to the manifold series. In this connection it is also an object of my invention to arrange the manifolds so that they can be easily cleaned out by removing a cap, plug, or similar device designed for the purpose. By my arrangement I avoid choking the manifold or header with scale or sediment and the consequent interruption of circulation and rupture of tubes.

By the arrangement which I have referred to in a general way I gain additional heating-surface within the same space limits of the ordinary cross-tube sectional boiler besides improving the circulation of the water within the tubes and in general giving greater efficiency. With these ends in view and with the general object of producing a highly-efficient boiler my invention consists of certain features of construction and combinations of parts, which will be hereinafter described and claimed.

Reference is to be had to the accompanying drawings, forming a part of this specification, in which similar figures of reference indicate corresponding parts in all views.

Figure 1 is a side elevation, partly in vertical section, of the boiler embodying my invention. Fig. 2 is an end view, partly in sec-

tion, on the line 2 of Fig. 1; and Fig. 3 is a detail section plan showing the connection between one of the manifolds and an adjacent header.

The boiler is provided with a steam-drum 10 of ordinary type, which connects at the end with oppositely-arranged and downwardly-extending downflow-tubes 11 and 11^a, which deliver into the end and middle portions of the two side headers 12, which form each practically an entire boiler side. The boiler is also provided on opposite ends with upper and lower headers 13 and 14, which are arranged in series, as shown clearly in Fig. 2, and the upper headers 13 are preferably of about twice the width of the lower headers 14. These headers are preferably pitched slightly, as shown in Fig. 1, and the upper headers each connect with the steam-drum by a pair of tubes 15, and each upper header has also below the tubes 15 and out of alignment therewith tubes 16, which extend into the steam-drum 10. Connecting the upper and lower headers 13 and 14 on opposite sides of the boiler are likewise inclined cross-tubes 17, and as the opposed upper and lower headers are of different width and practically break joints, as it were, it will be seen that each header 13 connects with two rows of tubes 17, while each header 14 connects with a single row. In this way all the heating-space is utilized and the desired pitch of the cross-tubes is maintained, it being well known that this pitch and the header and steam-drum connections are essential to quick steaming.

The lower headers 14 connect by tubes 18 with the mud-drums 19, which are arranged, as shown, below the grate-door and form a low-set boiler, and the lower headers 14 also connect by the nipples 20 with the manifold or door headers 21, which are arranged above the doors of the boiler, as shown clearly in Figs. 1 and 2. The manifolds connect together by a tube or nipple 22, and it will be seen that there may be a greater or less number of manifolds or door-headers without affecting the principle of the invention. The manifolds have suitable caps 23^b at the outer ends, (see Fig. 3,) which can be removed for cleaning purposes, and similar caps 23^a on the side headers 12 can be removed, so that a

cleaning instrument can be thrust longitudinally through the series of manifold-headers. Likewise a cap 14^a is provided on each header 14 opposite the connections 20 and tubes 17 to provide for cleaning out the tubes. This is shown in Fig. 3. The manifold can also connect with the mud-drums 19, as shown at 23 in Fig. 1, if desired.

An important feature of my invention lies in the arrangement of the horizontal cross-tubes 24, which are staggered so as to get the full benefit of the heat, and these are arranged at right angles to the cross-tubes 17 and connect the side headers at a point occupying the space caused by the incline of the said cross-tubes 17.

The mud-drums 19 connect with the side headers by nipples 25, and caps 26 are provided on the outside of the headers in line with the pipes or tubes 25, so that by removing the caps the tubes and drum can be easily reached for cleaning purposes.

From the foregoing description it will be seen that I provide a cross-tube sectional boiler having the heating-space entirely occupied, that the arrangement is such as to provide for quick steaming and a free circulation, and that the parts are also easily accessible for cleaning and repair purposes. It will be seen that the downflow of water from the steam-drum is amply provided for and that the upflow through the headers and cross-tubes is also well provided for.

A high-set boiler is one in which the mud-drums are above the door, and in this case manifolds are not necessary; but it will be seen that my connections outside of the manifolds, but including the tubes 24, can be used with a high-set boiler, as in this case the manifold is superseded by a mud-drum.

Having thus fully described my invention I claim as new and desire to secure by Letters Patent—

1. In a boiler of the kind described the manifolds having means for opening the ends, and forming a part of the circulation system and connected together end to end.

2. In a boiler such as described, the manifolds included in the boiler circulation and connected together by nipples said manifolds having means for opening the ends.

3. In a boiler such as described the combination of the side water-legs, the headers between the legs, the mud-drum below the headers, and the manifolds between the side water-legs, said manifolds being connected to

the water-legs, the headers, and the mud-drum.

4. In a boiler such as described the combination of the water-legs forming the boiler sides, and the manifolds arranged end to end between the water-legs and connected therewith, said manifolds having means for opening the ends.

5. A cross-tube sectional boiler comprising opposed headers, a steam-drum and mud-drums, inclined cross-tubes connecting the headers, side water-legs, and tubes connecting the water-legs and arranged in the space formed by the incline of the cross-tubes.

6. The combination with the cross-tube sectional boiler having opposed and inclined cross-tubes, of a series of tubes included in the circulation system and arranged in the space formed by the incline of the cross-tubes.

7. In a sectional cross-tube boiler, the combination with the cross-tubes of opposite pitch, of the water-legs forming the boiler sides and included in the circulation system, and tubes connecting the opposed water-legs in the space formed by the incline of the aforesaid cross-tubes.

8. In a cross-tube steam-boiler characterized by opposed headers and inclined opposed cross-tubes, the combination with such boiler of tubes included in the circulation and arranged at right angles to and below the said cross-tubes.

9. A boiler of the kind described comprising a steam-drum, water-legs forming the boiler sides and connected to the steam-drum by downflow-pipes, upper and lower opposed series of headers connected to the steam-drum and by cross-tubes with each other, tubes arranged below the cross-tubes and connecting the side headers, manifolds connected together and connected with the side water-legs, and mud-drums arranged between the water-legs, the said drums being connected to the water-legs and to the lower headers.

10. In a boiler such as described the combination of the manifold running above the fire-door, and a mud-drum arranged below the fire-door, the manifold and drum being connected together, and also included in the circulation system of the boiler.
